UNITED STATES PATENT OFFICE.

CAMILLO OLIVETTI, OF IVREA, ITALY.

TYPEWRITING-MACHINE.

1,356,652.

Specification of Letters Patent. Patented Oct. 26, 1920.

Application filed December 2, 1918. Serial No. 265,028.

To all whom it may concern:

Be it known that I, CAMILLO OLIVETTI, a subject of the King of Italy, residing at Ivrea, Kingdom of Italy, have invented certain new and useful Improvements in Type-writing-Machines, of which the following is a specification.

This invention relates to typewriting machines of the kind in which the types are caused, by means of levers actuated by the fingers of the operator, to strike against the inking ribbon which transmits the impressions to the paper on the platen.

The object of the present invention is to provide a novel disposition and construction of the operating levers for the purpose of obtaining a typewriter in which the writing is visible and in which the movement of the levers is as easy, rapid and uniform as possible and the construction and the assembling of the different parts are rendered easy and practical. One form which the improvements may take is illustrated by way of example in the accompanying drawings in which for greater clearness those parts of the machine have been omitted which do not directly relate to the invention.

Though the present invention is applicable to every kind of keyboard machine, as for example to the typewriter in which a type-bar bears one or more characters, the annexed drawings relate to a machine, which is provided with two characters for each type-bar.

The mechanism which actuates the carriage of the platen with relation to the type is not referred to either in the description or in the drawings, since it is not comprised in the present invention.

Figure I is a side view of the lever system which transmits movement from the key to the type-bar and from the said type-bar to the escapement, one of the central bars of the machine being shown by way of example.

Fig. II is a back view of the lever system which transmits the movement of the type-bar plate to the type-bar, and the movement of the universal-bar to the escapement. A lateral type-bar at the moment of being raised is shown by way of example.

Fig. III is a section of the rod which transmits the movement of the type-bar.

Fig. IV is a view of a place for holding the small springs which oppose the working movements of the type-bars; these springs

hasten the type-bars to their resting position.

Figs. V and VI are diagrammatic views of two analogous forms of mechanism.

Fig. VII is a side view of the form which can also be given to the first lever which is actuated by the key.

Fig. VIII is a detail of one of the parts which transmit movement from the lever to the escapement.

Referring to Figs. I and II, 1 represents the key which is struck by the finger of the operator. The stem 2 of the key is guided in the opening 3 formed in the plate 4 placed in front of the machine and fixed to the frame, and is connected by the pivot 5 to the key lever 6 which has the form shown in the drawing. This lever pivots on a pin 7 which, in practice, consists of steel wire fixed in a groove cut in a small block 8, and is guided in its movement by a slot made in the said block 8. The block 8 is connected to a plate 9 fixed to the frame of the machine. There are one lever 6 and one block 8 for each key of the machine and they are arranged in rows in the usual way on the key-board of the machine.

In Fig. I the plate 9 is represented in section with four rows of blocks 8 in the usual position for a "standard" keyboard.

It is to be observed that the plate 9 has elongated holes which give passage to the stems 2.

The movement of the key lever 6 is transmitted to the sub-lever 13 by the rod 11 which is connected by the pivots 10 and 12 to the said levers 6 and 13.

The pivots 10 and 12 may be cylindrical but preferably they are spherical. The pivot 12 may be held by spring pressure in the branches of a spring fork 17 which is provided at its extremity with a screw fixed to the rod 11. This spring fork is generally employed in typewriters and is not considered as part of my invention.

The sub-lever 13 is pivoted upon a wire 14 fixed in a recess in the plate 15 which has the section shown in the drawings.

This plate has practically the shape of an arc of a circle, (see Fig. II) and is provided with radial slots corresponding to each type-bar of the machine.

The movement of the lever 13 is transmitted to the type-bar 21 by a link 19 which is pivoted at 18 and 20 to said lever and type-bar respectively. The type-bar 21

made of steel plate, pivots on the wire 22, rises, and strikes, with its type-head 24 against the printing point O of the plate 29.

The link 19 may be constituted by two small plates 19 and 19' (Fig. III) of spring material, which clamp between them two spherical pivots 18 and 20. The ends of the pivot 18 are riveted to the two small plates, while the other pivot 20 is riveted only to the plate 19', the other end of pivot 20 being held by means of a small stem, which is engaged in a hole in the other small plate.

Owing to the resilience of the two plates 19-19', the stem of the pivot 20 can be forced out of the hole in which it normally is held and the plates can be spread apart in order to afford a passage to the extremity of the type-bar during the assembling of the machine.

20 The type-bar 21 normally rests adjacent its type-head 24 upon a pad or cushion 58 as in the ordinary typewriters.

The type-head 24 is bent at an angle equal to that formed by the type-bar with the vertical.

At their rear ends the type-bars are enlarged (Fig. I) and as in the "Underwood" machine, they are guided in slots cut in a cast iron plate or type-bar segment 28 fixed to the frame of the machine. In a suitable recess in this segment is fixed the tempered steel wire 22 on which the type-bars turn.

The extremity 25 of the type-bar is hooked so that it can be made to clasp the wire 22 without removing the wire.

The parts described are so constructed and disposed as to cause all the key levers 6 and the respective rods 11 to move practically in vertical planes which are parallel to the median vertical plane which passes through the printing point O.

All the pivots 12 must be placed at the intersection of the plane in which the lever 6 and the respective rod 11 move, with the plane of movement of the sub-lever 13, which is practically the plane of the corresponding slot of the plate 15.

All the links 19 move also in planes parallel to the said vertical median plane of the machine.

In order that the movement may be made under the most favorable conditions, the rod 11 should form with the imaginary straight line connecting an angle of about 165° at the commencement of the stroke; also the angle between the straight line connecting the pivots 12 and 14 and the line of the rod 11 should be nearly 90°.

The sub-lever 13 may be made in different shapes, but the shape shown in the drawings is the most convenient, preserving from dust the part guided in the slot of the plate 15.

The pivot 12 is on a projection 16 on the said lever 13 and this projection is bent

in order that its end, which carries the pivot 12, may lie in a vertical plane and keep practically this position during the action too.

The lower part of the sub-lever 13 has a slot 30 in which the pivot wire 14 can enter; this slot is analogous to the slots of the lever 6 and the type-bar 21, so that the levers 6 and 13 and the typebar 21 may be assembled and dismounted without removing the wires 7-14-22 upon which they turn. 75

In order to render the back movement of the type-bar more rapid and also for keeping the circular extremities of the slots cut in the sub-levers 13 and in the ends 25 of the type-bars fastened to the pivots 14 and 22, the lever 13 is provided with a spring 32 which is attached thereto at one end and at its other end to a small hook 33 fixed in an elongated hole 34 in the plate 35. 80

Of course, there will be as many springs 85 32, hooks 33 and holes 34 as type-bars, and the holes 34 will be so disposed in the plate 35 (see also Fig. IV) as to correspond to the radial slots in the plate 15.

The speed of movement of type-bar and 90 the impulse to be given by the finger on the key, in order to obtain the movement of the said type-bar depend upon the tension of the spring 32.

In order to regulate the tension of the 95 spring 32 and consequently the "touch" of the machine, the plate 35 may be more or less moved, parallel to itself. For this purpose the plate 35 is provided at its ends with two projections 37 on which are pivoted two 100 curved arms 38 carried by a rock shaft supported at its ends by two pivots 40 fixed to the frame of the machine.

To the lower part of the plate 35 toward its middle is fixed a small bar 41 which is 105 slidable endwise through an opening 42 in the frame of the machine. To the screw-threaded end of the bar 41 are applied a washer 43, and two nuts 44-45. By turning the nuts 44-45 the plate 35 may be more 110 or less removed from the plate 15 in order to vary the length and consequently the tension of all the springs.

As the bar 41, rigidly connected to the plate 35, is guided in the hole 42 and the 115 two pivots 36, also rigidly connected to said plate, are guided by the arms 38, the plate will always be caused to move practically parallel to itself.

In order to quicken its back movement 120 each type-bar bears toward its lower end a curved projection 23 which in its movement strikes against a plate 46 bent into the form of an arc, the center of which is the printing point O, said plate extending through 125 the entire angle in which are disposed the type-bars, so that each type-bar in its movement strikes against a part of the arc shaped plate 46. This plate 46 has a shape similar to the plate which in the "Underwood" type- 130

writers acts as universal bar and has a similar duty, viz., to impart a backward movement to the type-bar, to maintain the same in its place during the movement, and at the same time to transmit the movement to the escapement and to the ribbon, but is guided in its movement in a different way.

The plate 46 is reinforced both by a plate 47 which is attached thereto at its ends, and 10 by means of cross-plates 48 having openings in which are engaged two pivots 49 carried by two curved arms 50. These arms 50 are fixed to a rock shaft 31 whose ends move on two pivots 53 carried by two projections 52 15 fixed to the segment 28 which is fixed to the frame of the machine.

Rigidly connected to the system of the plates 46—47—48 is another plate 54 of suitable length provided at its end with a hole 20 which serves as a bearing for a pivot 55 fixed to an arm 56 mechanically connected to the little shaft 57 which transmits the movement of the type-bars to the escapement and to the ribbon elevating mechanism.

25 These mechanisms are omitted in the description as forming no part of the present invention.

A spring, not represented in drawings, 30 operating on the shaft 51 or on the arm 56 returns the parts to normal position.

The entire system, pivoting on the two fixed points 53 and on the fixed bearings of the shaft 57, being articulated at the points 49 and 55, moves practically parallel to 35 itself.

All pivots 53 and 49,—55—57 may be substituted by ball bearings to obtain a greater smoothness of working.

Moreover, the end of the plate 54 may be 40 shaped as a fork to receive the pivot 55 as shown in Fig. VIII, such arrangement facilitating the assembling of the machine.

In the above described movement, the 45 type-bar is pushed by the sub-lever 13 by means of the rod 11. Instead of being pushed the type-bar may be pulled as illustrated in the diagrammatic Fig. VII without any substantial change in the system of the movement.

50 The lever 6 may be formed in different shapes, among which is to be noted the shape illustrated in Fig. VII without any substantial change in the system of the movement.

55 I claim—

1. In a typewriting machine, the combination of a set of key levers; a set of type-bars; and a connection between each key lever and the corresponding type-bar comprising a sub-lever pivoted at one of its ends to the machine and connected intermediate of its ends with means for operating it, said means comprising a rod engaging said sub-lever and connected to the key lever, said

rod moving in a vertical plane parallel to 65 the median vertical plane of the machine in operating said sub-lever, and said connection also comprising a link pivoted at one end to the end of the sub-lever and at its other end to the type-bar, said link moving 70 also in a vertical plane parallel to the median vertical plane of the machine, substantially as described.

2. In a typewriter, the combination with the machine frame, the sub-levers and their 75 actuating devices, and the type-bars connected with the sub-levers; of a supporting plate with which the sub-levers are pivotally associated; an adjustable plate located in front of the supporting plate; a connecting spring between the adjustable plate and each sub-lever; and means for adjusting the second-named plate to regulate the tension of said springs comprising a rocking support for said plate and a guide on said 85 plate slidably and adjustably engaged with the frame to insure a bodily parallel movement of the plate during adjustment.

3. In a typewriter, the combination with the machine frame, the sub-levers and their 90 actuating devices, and the type-bars connected with the sub-levers; of a supporting plate with which the sub-levers are pivotally associated; an adjustable plate located in front of the supporting plate; a connecting spring between the adjustable plate and each sub-lever and means for adjusting the second-named plate to regulate the tension of said springs comprising a rocking support for said plate, a laterally-projecting 95 guide member slidably engaged in a guide opening in the adjacent portion of the frame to insure a bodily parallel movement of the plate during adjustment, and adjustable devices on said guide member to engage said 100 frame and thereby hold said member in adjusted position.

4. In a typewriter, the combination with the machine frame, the sub-levers and their 110 actuating devices, and the type-bars connected with the sub-levers; of a supporting plate with which the sub-levers are pivotally associated; an adjustable plate located in front of the supporting plate; a connecting spring between the adjustable plate and each sub-lever; and means for adjusting the second-named plate to regulate the tension of said springs comprising a rock shaft having a pair of lateral arms fixed to it, said 115 arms being pivoted at their free ends to the adjustable plate, and a laterally-projecting guide member on said plate slidably and adjustably engaged with the adjacent portion of the frame to insure a bodily parallel movement of the plate during adjustment.

120 In testimony whereof I affix my signature.

CAMILLO OLIVETTI.
